ARC EXTINGUISHING MEANS

Application filed May 10, 1929. Serial No. 361,865.

My invention relates to circuit interrupters and particularly to arc-extinguishing chambers therefor.

One object of my invention is to provide an arc-extinguishing device in which the arc shall be compelled to traverse a linear path so folded upon itself that the arc shall never traverse a given portion of the path more than once.

Another object of my invention is to provide an arc-extinguishing device in which the arc shall be compelled, by barriers to traverse a predetermined linear path.

It has been the practice to provide an arc-extinguishing chamber with a plurality of closely-spaced metallic plates that separate the arc, established at the contacts, into a series of short arcs. Arrangements have also been provided which caused the short arcs to rapidly traverse a circular path on the plates. It will be obvious that, if the arc persists for a sufficient length of time, it will again traverse portions of its original path. Such a structure is described by Joseph Slepian in his copending application, Serial No. 181,289, filed April 6, 1927, now Patent 1,784,760 dated December 9, 1930 and assigned to Westinghouse Electric & Manufacturing Company, the assignee of the present application.

In practicing my invention, I provide walls of arc-resisting material between the closely-spaced metallic plates, between which the arc is confined and caused to traverse a spiral path on the surfaces of the plates.

It is another object of my invention to provide an insulating material associated with the surface of an arc-extinguishing device to confine the arc, moving on the said surface, to a predetermined path.

It is a further object of my invention to provide the surfaces of metallic plates, upon which an arc is moved to be deionized and extinguished in the above described manner, with a refractory insulating material that shall provide a spiral path for the arc and thereby prevent it from retracing a path over any portion of the surface already traversed.

With these principles and objects in mind, my invention will best be understood by re-

ferring to the following description and drawings, wherein

Figure 1 is a sectional view of an arc-extinguishing device disclosing a deionizing plate embodying my invention.

Figs. 2, 3 and 4 are enlarged sectional views taken along the line II—II of Fig. 1, showing the different forms that embodiments of my invention may assume.

Fig. 5 is a broken central view of the structure illustrated in Fig. 1 disclosing a modified form of the structure embodying my invention.

In the above mentioned application of Joseph Slepian, a circuit interrupter is described having a deionizing chamber positioned adjacent the contact members. This deionizing chamber includes an enclosing member having a plurality of metal plates in parallel relation with each other, these plates being spaced apart a very short distance by insulating material. A suitable magnetic field is provided to draw the arc into engagement with the plates where it is broken up into a plurality of small arcs in series through the plates. The magnetic field is so arranged that a movement is imparted to the arcs to rotate them between the adjacent surfaces of the plates thereby preventing the excessive heating or volatilization of the plates. When the current of the circuit reaches zero value, during the course of its alternating cycle, the arcs will be extinguished and because of the rapid recovery of dielectric strength of the spaces between the surfaces, the arc will not restrike when the voltage of the circuit has again increased in value during the alternating cycle.

As set forth in the above application, plates 1 are employed, having an aperture 2 in the center thereof, about which an insulating ring 3, which is preferably of a heat-refractory material, such as asbestos, is positioned. An insulating border 4 is provided around the outer edge of the plate 1, to retain the plates in spaced relation and to confine the arc to the surface of the plates.

In practicing my invention, in order to prevent the arc, in passing over the surface of the plate 1 between the insulating members

3 and 4, from traversing the same path by travelling repeatedly about the central opening 2, I have provided the insulating material 5, shown in Fig. 1, in the shape of a spiral, 5 positioned on the plate 1 between insulating members 3 and 4.

As the arc is transferred to the plate 1 and acted upon by the field of the blow-out magnet, it will revolve about the central opening 10 2 and will be guided between the insulating members 3, 4 and 5 along a spiral path. Such an arrangement prevents any heating and burning of the metal which might occur under some conditions when the arc continues to travel repeatedly over the same path.

The structure of Fig. 1 shows a completely closed spiral path. In the event it is found desirable to permit the arc to retravel some 20 portion of the path more than once per interruption, the end of the innermost spiral may be left open as shown in Fig. 5, thus permitting the arc to repeatedly travel a spiral path. It will also be evident that the guiding wall of insulation may be made of configuration other than the spiral described above. Ways of arranging magnetic fields to cause an arc to traverse zig-zag or other multiple fold paths will be readily apparent 30 to those skilled in the art. Broadly, my invention comprehends the extinction of an arc by compelling it to travel only upon a predetermined linear path by reason of the fact that it is confined between insulating walls; 35 and the folding of the linear path which an arc is compelled to traverse.

In Fig. 2, the insulating members 5 are positioned equidistant from each other and are of such widths as to bridge the distance 40 between the adjoining plates 1; while such a structure prevents the arc from passing transversely from one section into another, it may be disadvantageous in certain applications, because it traps the accumulated gases and thereby impedes the rapid movement of the arc.

In Fig. 3, the insulating material 5 is an insulating cement that is placed on the surface of one of the plates and is spaced away 50 from the adjacent plate. Such a construction permits the gases to pass freely between the plates and, at the same time, marks out the path for the arc over the surface of the plates as the arc continues to travel in a spiral path.

In Fig. 4, a sectional view is shown similar to that of Figs. 2 and 3, with the exception that the insulating member 5 is mechanically supported in a spiral slot 6 in each alternate plate, so that the plates may be removed 60 without any danger of the insulating material being loosened or removed from its predetermined position. It will be recognized that it is possible to provide every plate instead of 65 every alternate plate with a spiral groove;

and to omit the solid insulating material also if desired. Thus a deionizing structure comprising a plurality of metal spirals positioned side by side is within the purview of my invention.

It will thus be seen that I have provided an arrangement comprising deionizing plates in which the arc is confined to a predetermined path and is prevented from traversing any portion of the path over which it had previously travelled. Other novel features of my invention are the method of mechanically attaching the insulating material to the plates and also the provision of short gaps that permit the gas to find egress from one space to another and thus to be carried away.

While I have described several embodiments of my invention, it is to be understood that many additions, subtractions, changes and substitutions may be made without departing from the spirit and scope of my invention. I desire, therefore, that the appended claims shall be limited only by the prior art.

I claim as my invention:

1. The combination with an arc-extinguishing chamber for a circuit interrupter, of a plurality of spaced metallic plates associated therewith, a magnetic field associated with the plates to cause an arc between said plates to move repeatedly thereon, and insulating guide members on the surface of the plates to cause the arc to move over different portions of the surfaces thereof.

2. The combination with an arc-extinguishing chamber, of a plurality of spaced metallic plates associated therewith, means for causing an arc established between the plates to repeatedly move thereon, and insulating means for guiding the said movement over a predetermined linear path upon the surface of the said plates.

3. The combination with an arc-extinguishing chamber, of a plurality of spaced conductors associated therewith, means for causing the arc established across the conductors to repeatedly move thereon, and means for compelling said arc to traverse a predetermined linear path.

4. The combination with an arc-extinguishing chamber, of a plurality of spaced conductors associated therewith, means for causing the arc established across the conductors to revolve on the surface thereof and means constituting a folded non-recurrent path for said arc.

5. The combination with an arc-extinguishing chamber for a circuit interrupter, of a plurality of spaced metallic plates associated therewith, means for causing series related arcs established between the plates to move on the surfaces thereof, and insulating means associated with said surfaces for compelling the arcs to traverse a tortuous path.

6. The combination with an arc-extinguish-

ing chamber, of a plurality of spaced conductors associated therewith, means for transferring the terminals of an arc to the surfaces of said conductors, means for moving the arc on said surfaces and means for compelling the arc to traverse a tortuous path thereon.

7. The combination with an arc-extinguishing chamber, of a plurality of spaced metallic plates associated therewith, means for transferring an arc to the plates to establish a plurality of series related short arcs therebetween, and means associated with a portion of the plates for providing confined paths for the arcs over the surfaces of the plates.

15 8. The combination with an arc-extinguishing chamber for a circuit interrupter, of a plurality of spaced metallic plates associated therewith, means for establishing an arc between the plates, and means associated with at least one of the plates for providing a non-recurrent path of revolution for the arc over the surface of the plates.

9. The combination with an arc-extinguishing chamber for a circuit interrupter, of a plurality of spaced metallic plates and a magnetic field to cause the arc between said plates to move thereon, and guide members on the plates so arranged that the arcs are caused to move only once over certain portions of the plate surface and repeatedly over other portions of its surface.

10. The combination with an arc-extinguishing chamber, of a plurality of spaced conductors associated therewith for dividing the arc into a plurality of short arcs, means for causing the arcs established across the conductors to move thereon, and means for compelling said arcs to repeatedly traverse a predetermined non-recurrent linear path.

40 11. The combination with an arc-extinguishing chamber, of a plurality of spaced conductors associated therewith, means for transferring an arc to the surfaces between the conductors, and means for compelling the terminals of the short arcs thus established to traverse a tortuous non-recurrent path.

12. The combination with an arc-extinguishing chamber, of a plurality of spaced conductors associated therewith for dividing the arc into a plurality of short arcs, and means for compelling said arcs to traverse a predetermined linear path without substantially lengthening the arc.

In testimony whereof, I have hereunto sub-
55 scribed my name this 7th day of May, 1929.

BENJAMIN P. BAKER.
